BIRD CAGE

Roger D. H. Lacock, Los Angeles, Calif.
(13437 Egbert St., Sylmar, Calif. 91342)

Filed Mar. 29, 1973, Ser. No. 346,118

Term of patent 14 years

Int. Cl. D30—02

U.S. Cl. D30—4

FIG. 1 is a perspective view of a bird cage showing my new design;

FIG. 2 is a rear elevational view; and

FIG. 3 is a top plan view.

I claim:

The ornamental design for a bird cage, substantially as shown and described.
